FIG. 2 is a perspective view of the first variant of the design shown in FIG. 1 fully opened with the screen folded down;

FIG. 3 is a perspective view of the variant of the design shown in FIG. 1 fully folded;

FIG. 4 is a left-side view of the variant of the design shown in the FIG. 1 fully opened;

FIG. 5 is a top view of the variant of the design shown in FIG. 1 fully folded;

FIG. 6 is a bottom view of the variant of the design shown in FIG. 1 fully folded;

FIG. 7 is a front view of the variant of the design shown in FIG. 1 fully folded;

FIG. 8 is a rear view of the variant of the design shown in FIG. 1 fully folded;

FIG. 9 is a left-side view of the variant of the design shown in FIG. 1 fully folded;

FIG. 10 is right-side view of the variant of the design shown in FIG. 1 fully folded;

FIG. 11 is a perspective view of a second variant of the design fully opened;

FIG. 12 is a perspective view of the variant of the design shown in FIG. 11 with both screens folded down;

FIG. 13 is a perspective view of the variant of the design shown in FIG. 11 fully folded;

FIG. 14 is a left side view of the variant of the design shown in FIG. 11 fully opened;

FIG. 15 is a top view of the variant of the design shown in FIG. 11 fully folded;

FIG. 16 is a bottom view of the variant of the design shown in FIG. 11 fully folded;

FIG. 17 is a front view of the variant of the design shown in FIG. 11 fully folded;

FIG. 18 is a rear view of the variant of the design shown in FIG. 11 fully folded;

FIG. 19 is a left-side view of the variant of the design shown in FIG. 11 fully folded;

FIG. 20 is right-side view of the variant of the design shown in FIG. 11 fully folded;

FIG. 21 is a perspective view of a third variant of the design fully opened;

FIG. 22 is a perspective view of the variant of the design shown in FIG. 21 with the top pair of screens folded down;

FIG. 23 is a perspective view of the variant of the design shown in FIG. 21 with the screens folded down;

FIG. 24 is a perspective view of the variant of the design shown in FIG. 21 fully folded;

FIG. 25 is a left-side view of the variant of the design shown in FIG. 21 fully opened;

FIG. 26 is a top view of the variant of the design shown in FIG. 21 fully closed.

FIG. 27 is a bottom view of the variant of the design shown in FIG. 21 fully folded;

FIG. 28 is a front view of the variant of the design shown in FIG. 21 fully folded;

FIG. 29 is a rear view of the variant of the design shown in FIG. 21 fully folded;

FIG. 30 is a left-side view of the variant of the design shown in FIG. 21 fully folded; and,

FIG. 31 is a right-side view of the variant of the design shown in FIG. 21 fully folded.
